UNITED STATES PATENT OFFICE

JAMES L. McCOSH, OF TULARE, CALIFORNIA

MATERIAL SUPPORT

Application filed December 14, 1928. Serial No. 326,054.

This invention relates to material supports and is directed more particularly to a material support for use in connection with display cabinets such as disclosed in either of my copending applications Serial Number 213,766, filed August 18, 1927, for display device, or Serial Number 326,055 filed December 14, 1928, for display cabinet, and, although particularly adapted for devices of this character, it will be understood of course that the support is not limited to such use, but in general it may be used in any other suitable or approved manner.

The primary object of the present invention is to provide a material support comprising an extensible arm that is movable within certain limits to either display the material outside of the cabinet or position it within the cabinet, and when moved to the display position shall engage a stop to normally prevent separation of the extensible arm and its support, but which is desired may be easily and readily detached therefrom to permit the material to be inspected under different light conditions.

Another object is to provide a material support of this character which may be easily and quickly removed or inserted as a unit structure with respect to the cabinet, thereby providing a flexible display device or cabinet which may be readily enlarged or diminished to suit the particular materials stored therein.

A further object is to provide a material support which shall include a neat and attractive attachment for holding a detachable card to clearly indicate the price, quality and other information relative to the material therein.

A still further object is to provide a material support of the aforesaid character which shall be simple in construction, inexpensive to manufacture, and which may be easily operated by the salesman.

With these and other objects in view, the invention may be stated to consist in the various novel features of construction and arrangement or combination, all of which will be fully described hereinafter and pointed out in the appended claims.

In the drawing accompanying and forming part of this application,

Fig. 1 is a perspective view of a material support constructed in accordance with my invention;

Fig. 2 is a side elevation of the support but with the extensible arm removed therefrom;

Fig. 3 is a bottom plan view thereof;

Fig. 4 is a fragmentary, vertical, sectional view through the extensible arm;

Fig. 5 is an elevation of the price tag holder, and

Figure 6 is a detailed view in elevation showing a cabinet employing my new material supports.

A material support embodying my invention comprises a substantially U-shaped supporting rod 10 having an upper, horizontally disposed portion 11, a lower, horizontally disposed portion 12, and a vertically disposed interconnecting portion 13. The end of the upper portion 11 is preferably flattened and deflected downwardly, as indicated at 14, to engage a rolled edge of the display cabinet not shown. Extending outwardly and downwardly from the intersection of the horizontal portion 11 and the vertical portion 13 is a rod 15 having an angularly disposed projection 16, and these elements are adapted to engage over a ring (not shown) adjacent the central portion of the cabinet and thereby detachably retain the material support in position in the cabinet.

The lower horizontal portion 12 of rod 10 is formed with a longitudinally disposed groove 18 which extends substantially the entire length thereof, as shown in Figs. 2 and 3. The outer end of portion 12 is flattened, as indicated at 19, and this flattened portion which is preferably arranged substantially 90 degrees from groove 18, merges with one end of said groove, through a slightly rounded shoulder, as indicated at 20.

Slidably mounted on the aforesaid horizontal portion 12 is a tubular material supporting arm 22 having a depressed portion 23 engaging in groove 18. It is therefore apparent that the tubular arm may slide longitudinally on horizontal portion 12 a distance defined by the depressed portion 23.

engaging the walls forming the ends of the groove as clearly shown in Fig. 3. When the supports are positioned in the cabinet these limits of movement for the tubular arm 22 will correspond to the material therein being completely in the cabinet or partially or completely removed therefrom for inspection and display. Should it be desired to remove the material to a distant point for inspection under different light or other reasons, the tubular arm may be completely extended, then rotated through 90 degrees and withdrawn completely from the horizontal portion 12. The point of merger 20 of the flattened portion with the end of groove 18 permits the depressed portion 23 to leave the groove, and the flattened portion 19 provides clearance for the element 23 when the tubular arm is completely withdrawn from the supporting rod 12.

The outer end of the tubular arm 22 is preferably fitted with a price tag holder 25 which not only finishes off the end thereof, but also affords a convenient receptacle for holding a tag to convey information regarding the particular material on the support. This holder is preferably formed from sheet metal and is provided with inturned side and bottom edges 26 and 27 respectively, forming a pocket for the price tag. The holder is also formed with a rearwardly projecting tubular portion 28 which snugly but detachably engages over the end of the supporting arm.

35. I claim:

1. A material support of the character set forth comprising a rod, a material support slidably mounted on said rod, means permanently attached to and interconnecting said material support and rod to normally limit the longitudinal movement of one with respect to the other but permitting complete removal of one from the other when desired, said means including a portion extending laterally in a curve, then longitudinally of said rod to facilitate such removal.

2. A material support of the character set forth comprising a rod having a groove therein, a material support slidably mounted on said rod and having a projection engaged in said groove, said projection being adapted to engage the walls defining the ends of said groove to limit the movement of said support on said rod, and means formed on said rod adjacent one end of said groove for disengaging said projection from said groove to permit removal of said support from said arm, said means comprising a slightly rounded shoulder leading laterally from said groove and communicating with a recessed portion.

3. A material support of the character set forth comprising a rod having a groove therein, a material support slidably mounted on said rod and having a projection engaged in

said groove, said projection being adapted to engage the walls defining the ends of said groove to limit the movement of said support on said rod, said rod having a flattened portion merging with one end of said groove and out of alignment therewith to permit said projection to be disengaged from said groove and said support removed from said rod.

4. A material support of the character set forth comprising a U-shaped member, one of the arms of said member serving to support said member and the other arm of said member having a longitudinally disposed groove therein, and a tubular material support slidably mounted on the last mentioned arm and having a projection engaging said groove, said projection being adapted to engage the walls defining the ends of said groove to limit the movement of said material support, and said last mentioned arm having a flattened portion disposed out of alignment with said groove and a rounded shoulder interconnecting said flattened portion and groove to permit removal of said material support from said arm.

5. A material support of the character set forth comprising a U-shaped member, one of the arms of said member serving to support said member and the other arm of said member having a longitudinally disposed groove therein, a tubular material support slidably mounted on the last mentioned arm and having a projection engaging said groove, said projection being adapted to engage the walls defining the ends of said groove to limit the movement of said material support, and means associated with said rod for disengaging said projection from said groove to permit removal of said material support from said arm.

In testimony whereof I affix my signature.
JAMES L. McCOSH.
